UNITED STATES PATENT OFFICE.

WILSON L. CAMPBELL, OF LA GRANGE, ILLINOIS, ASSIGNOR, BY MESNE ASSIGNMENTS,
TO FIRST TRUST AND SAVINGS BANK, TRUSTEE, OF CHICAGO, ILLINOIS.

COMMON-BATTERY AUTOMATIC TELEPHONE SYSTEM.

1,137,200.

Specification of Letters Patent. Patented Apr. 27, 1915.

Application filed July 9, 1907. Serial No. 382,900.

To all whom it may concern:

Be it known that I, WILSON L. CAMPBELL, a citizen of the United States of America, and resident of La Grange, Cook county, Illinois, have invented a certain new and useful Improvement in Common-Battery Automatic Telephone Systems, of which the following is a specification.

My invention contemplates an improvement on the apparatus and system disclosed in my application Serial No. 382,901, filed concurrently herewith. In said application the arrangement is such that the talking current is fed through the connector to the called telephone line, as well as through the windings of the trip magnet of the individual switch, of the called subscriber. In this case, however, as hereinafter described, the connector is employed for feeding talking current to the calling subscriber's line, but no current is supplied through the connector to the called line for talking purposes. In other words, certain windings of the called subscriber's individual trunking switch constitute the sole medium for feeding talking current to the called subscriber's line, so that the called subscriber's line receives talking current through the medium of the normal connection therefrom to the common battery. The calling subscriber's line, as stated, then receives talking current through the windings of the connector, as will hereinafter more fully appear.

In the accompanying drawings Figure 1 shows diagrammatically a calling substation A and a called substation A' connected through the medium of automatic switches C, D and E. To the line No. 500 of substation A there is allotted the switch C, of an improved type, known as a line switch; and to the line No. 220 of the substation A' there is allotted a similar line switch C'.

At D is represented a first-selector switch, and at E is shown a connector-switch in connection with which I have elected to explain my invention; the former being of the general type described in Patent No. 815,321, granted March 13, 1906, to Keith, Erickson & Erickson, and the latter being an improved form of the connector shown in Patent No. 815,176, also granted March 13, 1906, to Keith, Erickson & Erickson.

The master switch F is provided for controlling a group of line switches of which C is a member. For operating and talking

purposes a central battery B having its positive terminal preferably grounded at G is used.

Fig. 2 is an enlarged diagram of the line switch C and its master switch F. Fig. 60 3 is a detail view of the master switch bank. Figs. 4, 5, 6, 7, 8, 9 and 10 are detail views showing the construction and operation of the impulse springs of the subscriber's telephone. 65

It will be understood that the first-selectors and connectors may be employed upon a percentage basis—that is, in an automatic exchange of one-thousand capacity, a somewhat common arrangement is to divide the 70 subscribers and their allotted line switches into groups of one-hundred each. Then to each group of line switches there is allotted a group of first-selectors, usually ten in number, making in a one-thousand system 75 one-hundred first-selectors. Then to each bank level of these first-selectors there is allotted a group of connector-switches, usually ten in number, which in turn are adapted 80 to make connection with the subscribers' lines of that group. For example, the group corresponding to the first level is the one-hundred group; the group of the second level is the two-hundred group, etc.; thus to each hundred group of subscribers of the 85 thousand there is allotted a group of connector switches, so that in a one-thousand system there would be one-hundred connectors, when arranged on a ten per cent. 90 basis.

The substations may be of any suitable or approved type. Those in connection with which I have elected to explain my invention comprise, as shown at station A, a receiver 2, a switch-hook 3 for controlling the 95 substation circuits, which controlling operations are accomplished through the medium of any suitable means, such as the cam-arms 4, 5 and 6. As the switch-hook is lowered the cam-arm 5 momentarily presses the release springs 7, 8 and 9 into engagement, whereby the substation line conductors may be grounded simultaneously. When the switch-hook is down the cam-arm 6 maintains a contact between the springs 10 and 11, thereby bridging the ringer 12 in series 100 with the condenser 13 across the line. 105

The substation ground circuit is normally broken between the ground springs 14 and 15 by the cam-arm 4, but when said 110

2

springs are together ground potential is then provided to the ground post 16, and to the release spring 7, as is usually the case in telephones of this type. The said substation 5 comprises the usual transmitter 17, induction-coil 18 having the primary winding 19 and secondary winding 20. Being an automatic substation it is provided with the usual vertical and rotary impulse springs 21 and 22. The vertical impulse spring is provided with an oblique projection or lug 23 on its under side (Fig. 4) with which the vertical impulse teeth 24 are adapted to engage for driving the spring 21 intermittently 10 onto the ground post 16. The rotary impulse spring 22 is provided with a somewhat similar mechanism, by means of which the rotary impulse spring is driven onto the ground post once when the dial is rotated in one direction, and once when rotated in the opposite direction. The said rotary impulse spring 22 has on its under side a V-shaped member 25 having two sides *c* and *d*, and there is, in addition, an auxiliary spring 26 15 which works in conjunction with the V-shaped member. As shown more clearly in Fig. 4 the auxiliary spring 26 is provided with a lower curved part 27 having the rear section *e* curving outwardly, as shown in 20 Figs. 4, 5 and 6. The front section 28 of the said member 27 is designed to fall just below the apex of the V-shaped member 25, so that the rotary impulse tooth 29, when moved in the direction indicated by the arrow in Fig. 5, will pass onto the curved 25 member 27, thus pressing the rotary impulse spring 22 onto the ground post 16 for a comparatively long time, as shown in Fig. 6, and sending a comparatively long impulse to the line. As the impulse wheel advances, the vertical impulse teeth 24 approach the lug 23 of the vertical impulse spring 21 (Fig. 6), and eventually the first tooth that meets the lug 23 clears or disengages the said lug, 30 as shown in Fig. 7, but not until after the rotary impulse tooth 29 clears the curved member 27. As the impulse wheel continues to advance in the direction indicated by the arrow in Fig. 7, the succeeding impulse 35 tooth will clear the projection 23, as shown in Fig. 8. Then, when the impulse wheel is released, first the vertical impulse spring 21 is carried into engagement with the ground post 16 twice by the teeth previously cleared 40 or disengaged, as indicated in Fig. 9; but as the impulse wheel nears its normal position the rotary impulse tooth 29 passes under the curved member 27 of the auxiliary spring 26 (Fig. 10), engaging the V-shaped member 45 40 directly and for a short time only, sending the ordinary impulse through the medium of the rotary impulse spring 22 to the line, after which the said member 27 is cleared, as shown in Fig. 5, as the impulse 55 wheel reaches its normal position. As thus

described, the operations are repeated each time that the dial is turned, and the number of impulses produced through the medium of the vertical impulse spring are accurately and definitely determined at each operation 70 of the dial. Said substation is, of course, provided with a dial which is not shown, but which is secured to the shaft 30, together with the locking dog 31. Furthermore, there is a locking cam 32 that locks the dog 75 31 while the receiver is on the switch-hook, to prevent a rotation of the dial.

For operating the impulse springs 21 and 22 the substation is provided with an impulse wheel 33 that is secured to the shaft 30, 80 which impulse wheel carries on its periphery the so-called vertical impulse teeth 24 and one rotary impulse wheel 29. The said impulse teeth are so arranged that when the dial is drawn down the rotary impulse 85 spring 22 is pressed into contact with the ground post, and the impulse spring 21 is not carried into contact with the ground post 16; but as the dial returns, first the vertical teeth engage the vertical impulse 90 spring 21, and after they have completed their work the rotary impulse tooth 29 operates the rotary impulse spring 22. In this operation the subscriber's rotary line conductor 35 is given a so-called preliminary 95 impulse, then the vertical line conductor 34 is given a number of ground impulses, and then the rotary line conductor 35 is given another ground impulse. It will be seen that as long as the dial is out of normal position the dog 31 permits the primary circuit 100 springs 36 and 37 to separate, thus preventing the impulses that are delivered to either line conductor from passing to the other.

Means whereby a subscriber may signal 105 a called subscriber comprises the push-button 38 which, when pressed, carries the spring 39 out of engagement with the contact point 40 and into engagement with the contact point 41, whereby the vertical line 110 conductor 34 is grounded.

The line switch C (Fig. 2) comprises a plunger 42, plunger-arm 43, trip magnet 44 and switch-release magnet 45, all of which are built about a suitable base or frame not 115 shown. The said switch-release magnet is provided with an armature 46 that is pivoted on a pin 47 which rises from the base of the switch. The said armature carries pivotally secured on its end a second armature 48 that is controlled by the trip magnet 44. The pin 49 about which the armature 48 moves is carried on the end of the armature 46. The plunger 42 is pivotally secured by the pin 50 to the plunger-arm 43, which latter is in turn pivoted to a pin 51 that rises from the switch frame (not shown). The lug 52 is stamped out of the side of the frame and is provided as a stop or rest for the armature 46. Upon the armature 48 is 130

secured the catch spring 53 which is adapted to engage the end 54 of the plunger-arm 43. Furthermore, upon the end of the plunger-arm 43 there is the arm 55 having on its end the insulating bushing 56. This arm 55 is so arranged that when the plunger-arm operates and thrusts the plunger into the bank, the springs 57 and 58 are carried out of engagement with the springs 59 and 60, respectively, whereby the trip magnet coils are disconnected from the battery terminals. The trip magnet 44 comprises two double-wound coils 61 and 62, having the windings differentially arranged, so that when one set of windings of the two coils carries current the trip magnet 44 operatively energizes; but when both sets of windings are included in series in an energizing circuit the said magnet does not operatively energize.

The general operation of the switch is as follows: The trip magnet 44 is energized by a preliminary impulse sent over the rotary side of the line by the forward rotation of the dial, and the armature 48 is attracted against the magnet cores. When the armature 48 is attracted to the left (Fig. 2), the catch 53 slides out of contact with the end 54 of the plunger-arm 43, and the said plunger-arm 43, owing to the tension of the spring 63, moves about the pin 51 and thrusts the plunger 42 into the bank terminal Q. When the plunger-arm 43 thus operates, the arm 55 operates the springs 57 and 58 to disconnect the trip magnet from the battery, as explained; and when the trip magnet deenergizes, the trip armature 48 falls against the end of the plunger-arm 43. The switch is restored when the release magnet 45 becomes energized, whereby the armature 46 is attracted and, accordingly, the trip armature 48 is moved upwardly until the catch 53 slides over the end 54; then when the release magnet 45 becomes deenergized the armature 46 returns to normal position and remains at rest against the stop 52. Furthermore, since the plunger-arm 43 is now in engagement with the armature 48, the said plunger-arm is also moved about the pin 51, whereby the plunger 42 is removed from the bank terminal Q. Also, since the plunger shaft has advanced one step, the hub 64 of the plunger 42 comes to rest in the position shown by the dotted lines in Fig. 2, against the plunger shaft 65; and as the said plunger shaft advances each time an idle trunk is seized, the plunger 42 is not advanced, but remains in this position opposite the trunk terminal from which it has just disengaged, since the slot 66 is not in engagement with the plunger shaft 65. After all of the trunk lines have been successively seized, and the plunger shaft again passes to the position it occupied when the plunger 42 seized the terminal Q, the

plunger 42 now returns to normal locking engagement with the said plunger shaft. In the meantime, if the line switch C is again operated, the plunger 42 again engages the same terminal, the terminals usually being 70 ten in number, but only one of which is shown at Q. The said terminal is shown turned from its true position with respect to the swing of the plunger 42, and the bushing 67 is correspondingly turned, all 75 for the purpose of making the illustration clearer. The terminal Q comprises the springs 68 and 69, 70 and 71, 72 and 73, and 74 and 75. The said springs are normally disconnected from each other, but are 80 driven into contact in the above-mentioned order when the plunger 42 engages the terminal Q. Normally the plunger 42 is, however, retained out of engagement with the line switch bank, and in either locking or 85 sliding engagement with the plunger-controlling shaft 65, which latter is operated by the master switch F. By sliding engagement I mean that the slot 66 of the plunger 42 does not engage the plunger shaft 65, 90 and as the plunger shaft is turned the hub 64 slides upon the shaft; but when in locked normal position the slot 66 is in engagement with the shaft 65, and each time that the shaft is advanced the plunger 42 is also 95 advanced.

The master switch F, which may be of any suitable or approved type, is provided for operating the plunger shaft 65, and for controlling certain circuits that will be disclosed hereinafter. It comprises the following details: A motor magnet 76 for operating the ratchet wheel 77, which latter is designed for operating the plunger shaft 65 through the medium of the cam 78; also a 100 differential relay 79 for controlling the energizing circuit of the motor magnet 76. The said master switch also has a bank O comprising a plurality of individual contact segments *a* and a common metallic segment 80, 110 as shown in Fig. 3. The wiper 81 is adapted to remain in constant engagement with the bank O, and to maintain at all times, except when the wiper is passing from the extreme left contact 82 to the extreme right contact 115 83, some one of the segments *a* in electrical connection with the common segment 80. As shown in Fig. 3, the individual segments *a* are separated from the common segment by the insulating strips 84. The spring 85 is 120 provided so that when the wiper 81 passes to the last contact point 82, then on the next step the wiper is carried to the contact 83 on the extreme right and the upper part of the wiper 81 slides on the guide spring 85, 125 thus preventing the wiper from placing any of the individual segments *a* in contact with the common segment 80, whereby some interference might be caused with the master switch. The wiper 81 is operated in a step- 130

5 by-step manner by the ratchet wheel 77, through the medium of the cam member 78 rigidly secured to the said wiper 81 and adapted to successively engage the pins 86, 87, 88 and 89 upon the said ratchet wheel 77. The motor magnet 76 is provided with an armature 90 upon the end of which there is suitably secured a pawl 91. Each time that the said magnet is energized the pawl 91 engages the ratchet wheel 77, advancing the latter one step. It will be seen, therefore, that as the ratchet wheel 77 advances, the wiper 81 also advances step-by-step from right to left, and when the pin 86, for instance, clears the cam 78 the retracting spring 92 restores the wiper 81 to its first position at the right of the bank in engagement with the first segment 83. The said motor magnet 76 is provided with a couple 10 of interrupter springs 93 and 94 that are included in the energizing circuit of the said motor magnet, which energizing circuit also comprises the springs 95 and 96 controlled by the differential relay 79. Therefore, whenever the differential relay is energized 15 the springs 95 and 96 are pressed into contact, and the motor magnet 76 operates step-by-step as long as the differential relay 79 remains energized. Furthermore, it is assumed 20 that the terminal Q of the line switch C is the first terminal of the line switch bank. The plunger 42, while in normal locking engagement with the shaft 65, is retained in front of said terminal by the plunger 25 shaft 65 whenever the master switch wiper 81 is in engagement with the bank segment 83; but as the motor magnet 76 advances the wiper 81 onto the second segment 97, the said plunger and all idle plungers 30 similarly engaging the shaft 65 are carried opposite the next terminal of the line switch bank. It should be noted that in each switch bank all of the springs 68 are permanently connected and may be made of one 35 common piece. The springs 69, however, are individual—that is, there is one separate and distinct spring for every bank set Q, there being ten in the bank. The springs 70, 72, 73 and 74, like the spring 68, are also common, and the springs 71 and 75, like the 40 springs 69, are individual. For every bank terminal Q there is a trunk line of three conductors 98, 99 and 100 leading to a selector, and there is also a normal trunk line 45 comprising the conductors 101, 102 and 103 leading to the connector banks. The subscriber's line conductors 34 and 35 terminate in the springs 68 and 70 which, as has been stated, are common springs. When the subscriber 50 operates the line switch C and the plunger 42 engages the terminal Q, the subscriber's line conductors 34 and 35 are extended to the vertical and rotary trunk conductors 98 and 99, and thence to the switch D. 55 The mechanical details of the first-selector

are in general well known, involving the switch shaft (not shown) which carries the line wipers 104 and 105 and the private wiper 106. The side switch is controlled by the private magnet 107, and when the side switch is in normal or first position the side switch wipers 108, 109, 110 and 111 engage the contact points 112, 113, 114 and 115, respectively. In the second position the side switch wipers engage the contact points 116, 117, 118 and 119, and when the wipers are in third position the contact points 120, 121, 122 and 123 are engaged by their respective wipers. After the line switch C has operated and a trunk leading to a first-selector 60 has been seized, the first-selector is then under the control of the calling subscriber, through the medium of the vertical and rotary line relays 124 and 125. While the side switch is in first position the calling subscriber 65 controls the vertical magnet 126 which operates to give the switch shaft a vertical motion.

By means of the rotary line relay 125, and while the side switch is in first or second 70 position, the subscriber controls the private magnet 107 and, therefore, the side switch. When the side switch is in second position the rotary magnet 128 is energized, and the switch shaft that carries the wipers 104, 105 and 106 is operated in a rotary direction. The vertical and rotary line relays 124 and 125, acting conjointly, provide the means by which the release magnet 129 is operated by the subscriber while the side switch is in 75 first or second position. If the side switch passes to third position, however, (since the selector D is of the trunk-release type) the release magnet 129 is then controlled through the connector E by way of the private wiper 106 and by means of the back-release relay 130.

The mechanical details of the selector and connector, as is well known, are very much the same. For instance, the connector 80 switch shaft (not shown), like the selector, carries the line wipers 131 and 132 and the private wiper 133. The connector switch is also controlled by the calling subscriber through the medium of the vertical and rotary line relays 134 and 135. The vertical line relay 134 directly controls the vertical magnet 136 and also the rotary magnet 137. 85

The purpose of the vertical magnet 136 is to give the shaft and shaft wipers a vertical motion, and the rotary magnet 137 imparts to the shaft and shaft wipers a rotary or circular motion. The rotary line relay 135 controls the private magnet 138, which latter, under certain conditions, controls in turn 90 the vertical and rotary magnets 136 and 137, the release magnet 139 and also the side switch wipers 140, 141, 142, 143 and 144. Preferably, the said side switch, like the side 95 switch of the selector, has a normal or first 100

position, a second position and a third position. The release magnet 139 is also controlled by the vertical and rotary line relays 134 and 135 conjointly. By the use of the condensers 143 and 146 the circuit through the connector is divided into two sections. As shown, the connector is provided with a differentially-wound relay 147 which is composed of the windings 148 and 149. The function of this relay is to provide the calling subscriber with talking battery current. Furthermore, the connector is provided with a ringer relay 150 which is so arranged that when the connector side switch passes to third position an energizing circuit is closed through the said relay. By means of the differential relay 147 the energizing circuit through the ringer relay is controlled, and when the said relay 150 deenergizes, while the side switch is in third position, the ringer generator H is bridged across the terminals of the called line to signal the called subscriber. From the foregoing it is evident that the operation of the ringer relay, as arranged in the connector switch E, is just the opposite of the operation of the ringer relay as disclosed in the said connector patent—that is, to bridge the ringer generator across the called line the ringer relay must be deenergized, instead of energized as is usually the custom. The central station is equipped with the busy-signaling apparatus I of any suitable design, as, for example, the one comprising an interrupter 151 in series with the primary winding 152 of the induction-coil 153, whereby a busy-signaling current is induced in the secondary winding 154 of the said induction-coil 153. The secondary winding 154 is connected with the side switch wiper 144, and when the normal springs 155 and 156 are in contact, and the side switch is in first position, the busy-signaling current may be transmitted to the calling subscriber.

The operation of my improved line switch C may be more clearly understood from a description of its action when one subscriber calls another, as follows: To call substation A' (No. 220) the subscriber at substation A removes his receiver from the switch-hook and operates the calling device or dial once, in the well-known manner, for each digit—that is, when the dial is rotated for the first digit a preliminary impulse is transmitted over the rotary line conductor. This preliminary impulse energizes the trip magnet 44, whereby the line switch C is operated to seize an idle trunk line leading to a first-selector. The dial, in returning to normal position for the first digit, operates the first-selector switch to establish connection with an idle trunk line leading to a connector. It will be understood, of course, that when the dial is turned for each digit a preliminary rotary impulse is transmitted to the rotary

line by the forward rotation of the dial, which impulse, if the selector D or the connector E is on the line, is received by the rotary line relay of the switch while the side switch is in first position. This rotary line relay energizes, of course, but without effect, since the side switch is in first position, and the switch is not operated until the dial delivers the vertical impulses by its return rotation. Said preliminary impulse is effective only in operating the line switches. The impulses for the last two digits are directed toward the connector E, which operates to place its shaft wipers in connection with the contacts corresponding to the called line. The preliminary impulse for operating the line switch C, that occurs when the calling subscriber rotates the dial forward for the first digit, is caused by the rotary impulse spring 22 being pressed against the ground post 16. As a result of the impulse the trip magnet 44 of the line switch C is energized by a flow of current from ground G' to the springs 14 and 15, ground post 16, impulse spring 22 to the rotary line conductor 35, conductor 159 (Fig. 2), through the windings 160 and 161 of the trip magnet coils 62 and 61, cut-off springs 57 and 59 to the battery lead 162, thence through battery B to ground G. As soon as the trip magnet 44 energizes, the armature 48 is attracted, and the plunger 42 is liberated and thrust into the bank terminal Q (assuming that the plunger 42 is opposite this particular terminal at the time) by the spring 63. The plunger, upon thus operating, moves the plunger-arm 43 about the point 51, whereby the arm 55 on the end of the plunger-arm carries the springs 57 and 58 out of engagement with the springs 59 and 60. The disengagement of the springs 57 and 59 breaks the energizing circuit through the trip magnet 44; the said trip magnet then deenergizes and permits its armature 48 to fall back—that is, the spring catch 53 falls against the terminal piece 54, as shown. When the plunger 42 engages the bank terminal Q an energizing circuit is closed through the motor magnet relay 79, which in turn operates to close an energizing circuit through the motor magnet 76. The motor magnet then operates to advance all idle plungers that are in locking engagement with the shaft 65 to a point opposite the next idle bank terminal, similar to the terminal Q. The circuit through the relay 79 extends from ground g' through the winding 163 of the relay 79, segment 80, wiper arm 81, segment 83, conductor 164, bank terminal springs 75 and 74, release magnet 45 to the battery lead 162, thence through battery B to ground G. Although this circuit includes the release magnet 45, the magnet 45 does not operatively energize, since the windings of the relay 79 are of a high resistance, while the winding 163

6

of the release magnet is comparatively low. The relay 79 upon energizing operates to place the springs 95 and 96 in contact, whereby a circuit is completed through the 5 motor magnet 76, extending from ground G^2 through the springs 95 and 96, motor magnet springs 93 and 94, through the motor magnet 76 to the battery lead 162, thence through battery B to ground G. The motor magnet 76, upon energizing, attracts its armature 90, whereby the pawl 91 engages the ratchet wheel 77 and rotates the wheel one 10 step. When the armature 90 is attracted against the magnet cores the springs 93 and 15 94 disengage, thereby breaking the energizing circuit through the motor magnet. The cam 78, being in engagement with the pin 86, is operated to advance the plunger shaft 65, and consequently all idle plungers that may 20 be in normal locked position with the shaft 65, one step and to a point opposite another trunk terminal, similar to the terminal Q (assuming the next succeeding trunk to be 25 idle). Consequently the wiper 81 is carried from the contact point 83, which corresponds to the terminal Q, to the contact point 97, which latter corresponds to the terminal before which the advanced idle plungers are 30 now resting.

30 Suppose that nine subscribers have called and that the master switch has been thus operated nine steps, carrying the wiper 81 to the last contact point 82. Now, when the motor magnet 76 operates for the next 35 step, and when the tenth subscriber calls, the wiper 81 passes back and drops into engagement with the contact point 83, as already explained. If the first trunk is still busy the wiper 81 finds battery current 40 on the contact 83, and an energizing circuit is established through the differential relay 79, which in turn operates to close an energizing circuit through the motor magnet 76. The current through the said relay 79 flows 45 from the said contact 83 through the wiper 81 to the common segment 80, through the winding 163 of the differential relay 79 to ground G^2 . When the differential relay 79 attracts its armature the differential relay 50 95 and 96 are pressed into contact, thereby closing an energizing circuit for the motor magnet 76 from ground G^2 through the said springs 95 and 96, through the motor magnet springs 93 and 94, motor magnet 76, thence to the battery lead 55 162, and through battery B to ground G. The motor magnet then operates, as previously explained, to rotate the ratchet wheel 77 one step for advancing the plunger shaft 65 one step, and the master switch bank wiper 81 one step also, and into engagement with the second segment 97. The plunger shaft 65 when thus advanced one step carries all idle plungers that are in 60 65 locked engagement with the said shaft to

a point opposite the next bank terminal, as previously explained. If there should still be a guarding potential at the bank segment 97 of the master switch bank the differential relay 79 will remain energized, whereby the energizing circuit through the motor magnet 76 is again completed when the motor magnet springs 93 and 94 again engage; and as a result the motor magnet 76 is again operated, whereby the plunger 75 shaft 65 and the master switch wiper 81 are advanced another step. This operation continues as long as the wiper 81 continues to find segments with guarding potential. As soon as an idle segment is found, however, 80 the energizing circuit through the differential relay 79 is broken, at which time the said relay in turn breaks the energizing circuit for the motor magnet 76 until the next subscriber makes a call. At the instant that the plunger 42 enters the said bank terminal Q the following springs are 85 pressed into contact: 68 and 69, 70 and 71, 72 and 73, and 74 and 75.

90 The engagement of the springs 72 and 73 establishes a guarding potential by way of the normal conductor 103 to the connector private bank contacts corresponding to the line that terminates in the line switch C, to prevent any subscriber from calling the said line after the calling subscriber at 95 substation A operates his dial preparatory to making a call, as explained. The circuit over which the said guarding potential is established extends from ground G^4 through the bank springs 72 and 73 to the private normal conductor 103. Also, the closure of connection between the springs 74 and 75 establishes a guarding potential at the master switch bank contact 83, over the following circuit: From battery B to the battery lead 162, thence through the release magnet 45 and springs 74 and 75 over the conductor 164 to the said contact point 83. It 100 will be understood that the bank terminal Q, being the first bank terminal of the line switch bank, corresponds to the first segment 83 of the master switch bank O and, therefore, to the trunk line conductors 98, 99 and 100 which terminate in the selector D. This guarding potential protects the seized trunk conductors 98, 99 and 100 from being seized by other plungers, as already 105 explained. The closure of connection between the springs 68 and 69 extends the calling subscriber's vertical line conductor 34 to the vertical trunk conductor 98, and to the side switch wiper 108 of the first-selector D. The closure of connection between the springs 70 and 71 in a similar manner 110 extends the subscriber's rotary line conductor 35 to the rotary trunk conductor 99 and to the side switch wiper 109 of the selector D. The subscriber has thus established connection with the selector D, which latter is 115 120 125 130

now operated by the impulses that are delivered as the dial returns to normal position. The first digit being 2 the spring 21 is pressed onto the ground post 16 twice. 5 As a result the vertical line relay 124 of the first-selector D is energized each time by a flow of current from the substation ground G' through the springs 14 and 15 to the ground post 16, thence through the spring 10 21 to the vertical line conductor 34, line switch bank springs 68 and 69, vertical trunk conductor 98, side switch wiper 108 of the selector D, contact point 112, vertical line relay 124 to the battery lead 162, thence 15 through battery B to ground G. Each time that the vertical line relay 124 energizes, the line relay spring 166 is pressed onto the ground spring 165. The vertical magnet 126 is thereby energized, and the wipers 20 104, 105 and 106 of the selector D are raised to the second bank level and brought opposite the first contact of the level. The energizing circuit for the said vertical magnet 126 extends from ground G' through the 25 springs 165 and 166, private springs 167 and 168 to the vertical magnet 126, thence to the battery lead 162, and through battery B to ground G.

Following the vertical impulse the rotary 30 impulse spring 22 is pressed onto the ground post 16, grounding the rotary line conductor 35 and energizing, therefore, the rotary line relay 125 of the selector D. The energizing current passes from ground G' to the rotary line conductor 35, thence it flows through the line switch bank springs 70 and 71, rotary trunk conductor 99, side switch wiper 109 of the selector D, contact point 113 to the rotary line relay 125, thence to the battery lead 162, and through battery B to ground G. The rotary line relay upon energizing presses the line relay spring 169 onto the ground spring 165, thereby establishing a circuit through the private magnet 107 35 from ground G' through the springs 165 and 169 to the private magnet 107, and through the said magnet to the battery lead 162, thence through battery B to ground G. The private magnet, upon energizing and de- 40 energizing, permits the selector side switch to pass from first to second position, permitting the side switch wipers 110 and 111 to engage the contact points 118 and 119, respectively. The closure of connection between the side switch wiper 110 and the contact point 118 sets up an energizing circuit for the rotary magnet 128 from ground G' to the contact point 118, through the side switch wiper 110, interrupter springs 170, rotary magnet 128 to the battery lead 162, thence through battery B to ground G. The 45 said rotary magnet 128 then operates to rotate the wipers 104, 105 and 106 of the selector D into engagement with the first contact of the second level of the selector D, 50

from which contact it is assumed the trunk line conductors 171, 172 and 173 lead to the connector E. If the first trunk is busy, however, and the wipers have to pass over busy trunk lines, then as soon as the private wiper 106 engages the first grounded private bank contact point, the private magnet 107 energizes again, locking the side switch in second position. The energizing circuit for said private magnet extends from the grounded 55 terminal G of battery B through an occupying switch (not shown) to the private wiper 106, thence over the conductor 174 and through the back-release relay 130 to the side switch wiper 111, contact point 119, private 60 magnet 107, thence through said magnet to the battery lead 162, and through battery B to ground G. The private magnet 107, upon thus becoming energized, locks the side switch wiper 110 in engagement with the 65 contact point 118, whereby the rotary magnet 128 will be energized step-by-step until the wipers are carried beyond the last busy trunk line. At the instant that the private wiper leaves the last busy contact point the 70 energizing circuit through the private magnet 107 is destroyed, and as a result the selector side switch passes to third position. If, however, there are no busy trunk lines the private magnet 107 releases the side 75 switch to third position as soon as the wipers are carried into engagement with the first trunk line. As soon as the side switch passes to third position, as stated, the subscriber's line conductors 34 and 35 are extended to the 80 conductors 171 and 172, which in this case, it is assumed, lead to the connector switch E. The extension of the line occurs, of course, as soon as the side switch wipers 108 and 109 engage the contact points 120 and 121, respectively. Not only is the subscriber's line thus extended, but a guarding potential is 85 established at the private wiper 106 when the side switch wiper 111 passes onto the ground contact point 123, for protecting the seized 90 trunk line from interference by other calling subscribers. This guarding potential is established from ground G' to the contact point 123, thence through the side switch wiper 111 and through the back-release relay 130, conductor 174 to the private wiper 106. It will be seen, of course, that the energizing circuit for the rotary magnet 128, to 95 which reference has already been made, is destroyed when the idle trunk line is seized—that is, when the side switch wiper 110 leaves the contact point 118. The grounding of the line conductors 34 and 35 for the last two digits affects the connector by operating the vertical and rotary line relays 134 100 and 135. When the said vertical line conductor 34 is grounded the vertical line relay 134 is energized by a flow of current from the substation ground G', vertical impulse spring 21 to the vertical line conductor 34, 105

bank springs 68 and 69, trunk conductor 98, side switch wiper 108, shaft wiper 104, conductor 171, through the connector vertical line relay 134, winding 148 of the differential relay 147 to the battery lead 162, thence through battery B to ground G. The winding 148 of the relay 147 being included in this circuit, the said relay energizes, but its operation at this particular time is without effect. Each time that the vertical line relay 134 operates for the second digit, the vertical magnet 136 operatively energizes to carry the shaft wipers 131, 132 and 133 in a vertical direction, one step at a time, until the said wipers are carried up two steps and thus brought opposite a level in which are located the terminals of the line #220.

The circuit through the vertical magnet 136 extends from ground G^a through the springs 176 and 177, private magnet springs 178 and 179, vertical magnet 136, side switch wiper 142 to the battery lead 162, thence through battery B to ground G. When the rotary line conductor 35 is grounded, following the grounding of the vertical line conductor, the connector rotary line relay 135 becomes energized through a circuit extending from the substation ground G' through the rotary impulse spring 22, rotary line conductor 35, bank springs 70 and 71, conductor 99, side switch wiper 109, shaft wiper 105, conductor 172, rotary line relay 135, winding 149 of the differential relay 147, through the springs 180 and 181 to the battery lead 162, thence through battery B to ground G. The winding 149 of the differential relay 147 being included in this circuit, as is the winding 148 in the vertical line relay circuit, the said relay energizes, but with no effect. The rotary line relay 135 upon energizing operates to close an energizing circuit through the private magnet 138, which latter in turn operates to release the side switch from first to second position. The energizing circuit through the private magnet 138 extends from ground G^a through the springs 176 and 182, through the private magnet 138, springs 180 and 181 to the battery lead 162, and through battery B to ground G. For the last digit the subscriber operates the dial as previously described, grounding the vertical line conductor 34 ten times and the rotary line conductor 35 once. The connector vertical and rotary line relays 134 and 135 are operated over previously traced circuits. However, when the vertical line relay operates, a circuit is closed through the rotary magnet 137 instead of through the vertical magnet 136, since the side switch wiper 142 is now in second position. Each time that the rotary magnet is energized the shaft wipers 131, 132 and 133 are rotated one step at a time until the said wipers are carried into engagement with the normal conductors 183,

184 and 185, the first two of which conductors lead to the line terminals of the desired substation. The rotary line relay 135 upon energizing completes an energizing circuit through the private magnet 138, as before, which latter now operates with one of two results, namely the release of the side switch from second to third position, or the so-called busy-release of the connector. It will be assumed that the former result occurs and that the side switch passes to third position, whereby the side switch wipers 140 and 141 are placed in connection with the shaft wipers 131 and 132, respectively. Furthermore, when the side switch passes to third position a guarding potential is established for protecting the called line. This potential extends from ground G^a through the side switch wiper 143, conductor 186 to the private wiper 133 which engages the private contact of the called line. When the side switch wiper 142 engages the contact point 187 an energizing circuit is established through the ringer relay 150, whereby the connector shaft wipers 131 and 132 are disconnected from the ringer generator terminals and connected with the calling subscriber's extended conductors, and the calling substation is provided with battery current for talking purposes. The circuit through the ringer relay 150 extends from ground G^a, side switch wiper 143, conductor 186 through the winding of the ringer relay 150, differential relay springs 188 and 189, contact point 187, side switch wiper 142, battery lead 162, thence through battery B to ground G. The ringer relay upon energizing operates to shift the springs 190, 191 and 180 out of engagement with the springs 192, 193 and 181 and into engagement with the springs 194, 195 and 196, respectively. When the spring 180 is shifted from the spring 181 into engagement with the spring 196 the conductor 197 is changed from the negative pole of the battery B to the grounded positive pole. In order to signal the called subscriber the calling subscriber presses the signaling button 38, whereby the vertical line conductor 34 is grounded and the connector vertical line relay 134 and the differential relay 147 become energized as before. At this particular time, when the relay 147 operates to separate the springs 188 and 189, the energizing circuit through the ringer relay is broken. The said relay deenergizes and permits the springs 190, 191 and 180 to resume their normal position, whereby the ringer generator terminals are bridged across the line terminals of the called substation.

A signaling current is sent from the generator H to the ringer relay springs 193 and 191, side switch wiper 140 shaft wiper 131, vertical normal conductor 183, vertical

line conductor 198, condenser 199, ringer 200, springs 201 and 202 to the rotary line conductor 203, rotary normal conductor 184, shaft wiper 182, side switch wiper 141, ringer relay springs 190 and 192 back to the ringer generator H. As soon as the calling subscriber ceases to press the signaling button 38 the energizing circuit through the vertical line relay 134 and differential relay 147 is broken. When this circuit is broken the differential relay springs 188 and 189 again engage and reestablish the energizing circuit through the ringer relay which operates as before. The subscriber at substation A', in response to the signal, removes the receiver 204 from the switch-hook 205, which allows the springs 206 and 207 to engage, and the springs 201 and 202 to disengage, thereby removing the ringer 200 from across the line. The engagement of the springs 206 and 207 closes a series circuit through the windings of the trip magnet 208 of the line switch C' and the transmitter 209 and primary winding 210 of the substation A'. This circuit extends from ground G¹⁰ through the springs 211 and 212, windings 213 and 214 to the vertical normal conductor 183, vertical line conductor 198, springs 207 and 206, push button 208 ton springs, transmitter 209, primary winding 210 to the rotary line conductor 203, rotary normal conductor 184, through the windings 215 and 216, springs 217 and 218 to the battery lead 162, thence through battery B to ground G. The windings of the line switch trip magnet are so arranged that when the windings 213 and 214 thus carry current in series with the windings 215 and 216, the said magnet does not operatively energize. The above circuit through the trip magnet 208 provides the called substation with battery current for talking purposes. The calling substation is provided with talking battery current when the ringer relay energizes upon the passage of the side switch wiper 142 to third position. The circuit over which this current passes extends from ground G¹¹ through the springs 196 and 180, conductor 197, winding 149 of the differential relay 147, rotary line relay 135 to the trunk conductor 172, shaft wiper 105, side switch 109, trunk conductor 99, springs 71 and 70, to the rotary line conductor 35, thence through the primary winding 19, transmitter 17, contact 40, spring 39, springs 36 and 37 to the vertical line conductor 34, springs 68 and 69, trunk conductors 98, side switch 108, wiper 104, trunk 171, vertical line relay 134, winding 148 of the differential relay 147 to the battery lead 162 thence through battery B to ground G. The vertical and rotary line relays being included in this circuit energize and place the trunk-release springs 219 and 220 in contact, but at this time without effect.

The differential relay 147, thus carrying current in both windings in series, does not operatively energize. The two substation A and A' being thus provided with battery current for talking purposes, conversation may be carried on over the circuit shown by the heavy line conductors in Fig. 1.

The release of the switching apparatus is brought about when the calling subscriber restores the receiver 2 to the switch-hook 23, thereby pressing the release springs 7, 8 and 9 into engagement for a moment. The contact of said release springs grounds the vertical and rotary line conductors 34 and 35 simultaneously from ground G' to the release spring 7, thence through the springs 8 and 9 to the rotary and vertical line conductors. The grounding of the rotary line conductor 35 produces a short-circuiting or short-circuiting of the rotary line relay 135 in series with the winding 149 of the differential relay 147, said circuit extending from ground G' through the springs 123 and 186, conductor 197, winding 149 of the differential relay 147, rotary line relay 135, conductor 172, to the shaft wiper 105, side switch wiper 109, trunk conductor 99, bank springs 71 and 70 to the rotary line conductor 35, release springs 8 and 7 to the substation ground G'. Therefore, since the winding 148 of the differential relay 147 alone carries current, the said relay becomes energized and attracts its armature, which shifts the spring 189 out of contact with the spring 188. The disengagement of the springs 188 and 189 destroys the energizing circuit through the relay 150, and the spring 180 passes out of engagement with the spring 196 and into engagement with the spring 181, which removes the said short-circuit of the rotary line relay 135 and winding 149, and establishes an energizing circuit instead extending from the substation ground G' through the release springs 7 and 8 to the rotary line conductor 35, thence to the rotary line relay 135, as previously traced, winding 149 of the differential relay 147, through the springs 180 and 181 to the battery lead 162, thence through battery B to ground G. The rotary line relay 135 now operates, and the springs 220 and 219 come into contact, whereby an energizing circuit is established through the release magnet 139 of the connector E and the back release relay 130 of the selector D. However, the current now in passing, as above stated, through the winding 149 aids the winding 148 in maintaining the springs 189 and 188 disengaged.

The energizing circuit through the back release relay 130 and release magnet 139 extends from ground G' at the selector D, side switch wiper 111, back release relay 130, conductor 174, shaft wiper 106, conductor 173, trunk-release springs 219 and 220, re-

lease magnet 139, conductor 197, springs 180 and 181 to the battery lead 162, and through battery B to ground G. When the connector release magnet 139 is thus supplied with current it energizes, and as a result the switch shaft and side switch are restored to normal position, thus breaking the connection between the connector switch shaft wipers 131, 132 and 133 and the normal conductors 183, 184 and 185. The back-release relay 130, being in the same circuit with the release magnet, energizes simultaneously with the latter and operates to close a circuit through the selector release magnet 129 by pressing together the back-release springs 222 and 223. Also, when the springs 222 and 223 engage an energizing circuit is closed through the release magnet 45 of the line switch C extending from ground through the springs 222 and 223, bank springs 75 and 74, release magnet 45 to the battery lead 162, thence through battery B to ground G. The circuit through the said release magnet 129 extends from ground through the release springs 222 and 223, through the release magnet 129, thence to the battery lead 162, and through battery B to ground G. When the ground to the line conductors 34 and 35 is interrupted all the magnets involved in the release are de-energized and all the switches are fully restored. If the called line #220 is busy at the time that the calling subscriber #500 attempts to establish connection, the connector E is released by the last impulse to the rotary line conductor 35, as follows: The said impulse energizes the rotary line relay 135 of the connector E, which relay in turn energizes the private magnet 138, pressing the private springs 224 and 225 into contact after the private wiper 133 has been carried onto the grounded private bank contact. Of course, it is understood that whenever the line #220 is busy the connector private bank contacts connected with the private normal 185 are all connected to ground. Therefore, since the connector side switch is in second position when the private magnet springs 224 and 225 are brought into contact, an energizing circuit is established through the release magnet 139 from the said grounded private bank contact to the private wiper 133, thence to the side switch wiper 143 (which is in second position) to the private magnet springs 224 and 225, to the release magnet 139, through the springs 180 and 181 to the battery lead 162, thence through battery B to ground G. The connector switch shaft and side switch are thus released and connection is not established with the called line. Now, when the calling subscriber presses the signaling button, the vertical line relay 134 becomes energized and operates to close a circuit through the vertical magnet 136. The vertical magnet

operates to carry the switch shaft vertically, whereby the off-normal springs 155 and 156 engage to permit the busy-signaling current to pass to the called subscriber in the usual way. Of course, when the subscriber hangs up his receiver after receiving the busy-signal, he grounds the line relays 134 and 135 of the connector E, as already explained, producing the release of the switching apparatus as formerly. From the foregoing it will be seen that no talking current passes through the connector to the called subscriber's line, as the windings 213, 214, 215 and 216 of the trip magnet are the only resistance windings by which the battery is normally bridged across the called subscriber's line. In other words, the called subscriber's line receives talking current through the medium of its normal connection with the opposite poles of the common battery, and through no other medium. The calling subscriber's line, however, receives talking current through the medium of the windings of the line and differential relays in the connector, and these line relays are energized during conversation. The differential relay, however, remains de-energized until the calling subscriber hangs up his receiver, at which time the differential windings are unbalanced and a release is effected. It will also be seen that during conversation the trip magnet which is individual to the called subscriber's line is not energized, as its windings oppose each other when connected in series.

It will be understood, of course, that the windings of the trip magnets have sufficient impedance to prevent the passage of voice-currents therethrough. When one subscriber calls another the trip magnet of the calling line has its bridge cut off or opened up, but the trip magnet of the called line remains connected therewith to serve as a means for feeding talking current thereto. It will be seen that the called subscriber's trip magnet does not energize when he hangs up his receiver, for the reason that at such time there is no ground connection with the line at the substation. In other words, the called subscriber has not operated his dial, and consequently the ground connection which is used for releasing purposes is not closed, and the downward movement of the switch-hook does not ground the line. Of course, when the subscriber calls, he then puts the ground connection into condition to be closed by the downward movement of the switch-hook, so that the calling subscriber upon hanging up his receiver energizes the release mechanism of the connector and effects the release or disconnection between the lines.

It will be obvious that in this system the resistances of the magnets may be varied to any extent consistent with the successful

operation of the same. Not only may the resistances of the line relays (for example the line relays 124 and 125 of the selector D) be varied, but the resistances of the operating magnets (for example the release magnets 45, 129 and 139) may likewise be varied. It is also obvious that the springs used as contacts may be adjusted in any manner desired and their tensions varied 10 to any extent in order to control the speed and operation of the armatures associated with them. For example, the springs of the motor magnet relay 79 may be stiffened or weakened, as may be found convenient or 15 desirable.

Attention is called to the coils 44 of the line switch C. As shown, the windings of each of these coils should never be superimposed—that is, the windings on each coil 20 should be separated as shown, and in a manner more particularly illustrated in the motor magnet relay 79. In regard to this motor magnet relay it should be stated, and it is perfectly obvious, that, although it is 25 shown as a double-wound differential coil, the upper winding is not absolutely necessary, since the system will operate without it.

What I claim as my invention is:—

30 1. In a telephone system, a called subscriber's line, a switch individual thereto for trunking therefrom, provided with a controlling magnet connected in the line circuit, means for feeding talking current 35 through the said magnet to the called line, said magnet having windings constituting the sole resistance for regulating the flow of talking current to the line, a calling line, a manually-operated calling mechanism therefor, and means for extending connection 40 from the calling line to the called line, said means including an automatic switch individual to the calling line and responsive to and simultaneously with the manual 45 operation of said calling mechanism.

2. In a telephone system, a plurality of lines, automatic means for trunking a calling line into connection with a called line, comprising individual trunking switches for 50 the said lines, a connector for finding the called line, a calling mechanism for each line, said connector responsive to a varying number of impulses in accordance with the different digits of the called number, 55 means including a trunk line for feeding talking current to the calling line, all talking current for the called line being fed directly through elements of the individual switch thereof.

3. In a telephone system, a called line, a connector for seizing said line, said connector provided with a relay adapted to remain energized during conversation, means by which the calling subscriber de- 60 energizes said relay to signal the called sub-

scriber, trunk lines, an individual trunking switch for the called line, said individual switch provided with electromagnet windings, means for supplying talking current through said electromagnet windings to the 70 called line, and a calling mechanism for controlling said connector, which connector is operated by a varying number of impulses in accordance with the different digits of the called number. 75

4. In a telephone system, automatic means for extending connection from a calling line to a called line, a common battery normally connected to the called line, means by which the called line receives talking current only 80 through the medium of its normal connection with said battery, and means for opening said normal connection when the called line becomes a calling line.

5. In a telephone system, subscribers' 85 lines, individual trunking switches for said lines, each switch provided with a differentially-wound trip magnet normally bridged across its allotted telephone line, a releasable plunger-arm controlled by each trip 90 magnet and provided with means for opening the bridge thereof when the subscriber calls, means for supplying talking current through the trip magnet of a called line, the differential windings of said trip magnets preventing actuation of the called subscriber's individual switch during conversation, a ringer relay for controlling the flow of ringing current to the called subscriber's 95 line, and means for de-energizing said ringer 100 relay to signal the called subscriber.

6. In a telephone system, a calling subscriber's line, a called subscriber's line, an automatic connector common to said lines, means for supplying talking current to the 105 lines, said connector included in the path of talking current to the calling line, but excluded from the path of talking current to the called line, and a calling mechanism for controlling said connector, which latter is 110 operated by a varying number of impulses in accordance with the different digits of the called number.

7. In a telephone system, automatic means for trunking a calling line into connection 115 with a called line, including an automatic connector controlled by the calling subscriber, means for supplying talking current to the lines, said connector included in the path of talking current to the calling line, 120 but excluded from the path of talking current to the called line, and a calling mechanism for controlling said connector, which latter is operated by a varying number of impulses in accordance with the different 125 digits of the called number.

8. In a telephone system, a called line, means common to two or more subscribers for seizing said line, an automatic switch responsive when the said line is used as a 130

- calling line, but adapted to remain normal when the line is called, means for supplying current through elements of said switch to the called line for talking purposes, a ringing relay adapted to be energized during connection with a called line, and means for deenergizing said relay for applying ringing current to said line.
9. In a telephone system, a called line, an automatic connector common to two or more subscribers for seizing said line responsive to the call, an automatic switch responsive when the said line is used as a calling line, but adapted to remain normal when the line is called, means for supplying current through elements of said automatic switch to the called line for talking purposes, a ringing relay adapted to be energized during connection with a called line, and means for deenergizing said relay for applying ringing current to said line.
10. In a telephone system, a called line, an individual trunking switch therefor responsive only when the line is used as a calling line, means for seizing said line responsive to a call, means for supplying current through elements of said individual switch to the called line for talking purposes, a ringing relay adapted to be energized during
- 25

connection with a called line, and means for deenergizing said relay for applying ringing current to said line.

11. In a telephone system, a called line, a non-numerical trunking switch individual to said line, responsive only when the line calls, means for seizing said line responsive to a call, means for supplying current through elements of said switch to the called line for talking purposes, a ringing relay adapted to be energized during connection with a called line, and means for deenergizing said relay for applying ringing current to said line.

12. In a telephone system, means comprising automatic switches for connecting calling lines with called lines, means common to subscribers for feeding current to calling lines, and means whereby the called lines receive talking current only through connections which are individual thereto from a common battery.

Signed by me at Chicago, Cook county, Illinois, this 26th day of June, 1907.
